Patented Jan. 19, 1926.

UNITED STATES PATENT OFFICE.

RALPH H. MCKEE, OF NEW YORK, N. Y.

MOTOR FUEL.

No Drawing.

Application filed November 19, 1923. Serial No. 675,728.

To all whom it may concern:

Be it known that I, RALPH H. MCKEE, a citizen of the United States, residing at New York, in the county of New York and State of New York, have invented certain new and useful Improvements in Motor Fuels, of which the following is a specification.

This invention relates to motor fuels, and, in its preferred embodiment, it comprises a mixture of shale oil, benzol, and alcohol containing a small amount of ethylene or propylene.

In a copending application filed January 16, 1922, Serial No. 529,771, now Patent No. 1,494,613, granted May 20, 1924, I have described and claimed a motor fuel employing as a base, the gasoline like fractions of shale oil and more particularly a mixed fuel consisting of such gasoline like fractions of shale oil, alcohol and ether.

The present invention consists of such gasoline-like fractions of shale oil, alcohol, and ethylene or propylene. Ethylene and propylene are gases at ordinary temperatures and pressure but are readily soluble in alcohol and in a mixed fuel of the character described. While the proportion of ethylene or propylene employed may vary within certain limits, I find that a fuel containing from 2 to 8 per cent of either of these gases, or a mixture of them, is preferable.

Ethylene or propylene may be readily mixed with shale oil and particularly the gasoline-like fraction of shale oil to obtain the advantages usually obtained from the use of ether in mixed fuels, such as easy starting without the attendant disadvantages normally present in the use of ether in mixed fuels having petroleum oils as their base. The gasoline-like fractions of shale oil employed is preferably the fraction having a gravity of .650 to .740 and distilling between 100° F. and 350° F. Such fractions have a flash point at quite low temperatures, even below 32° F. Such fractions, when of the unrefined shale naphtha, are strongly odored due to the presence of nitrogen bases.

In a typical embodiment of the invention, I employ about one-third shale oil distillate from which the pyridines and isoquinolines have not been removed, one-third commercial benzol consisting of benzol and a small amount of toluene, and one-third alcohol consisting of alcohol and an amount of

ethylene or propylene, or mixture thereof, sufficient to form from 2 to 8 per cent of the entire mixture. The proportions may be varied within wide limits. Under some conditions, the shale oil derivative present may be employed in large percentages up to and in excess of 50 per cent, and the alcohol and benzol may be accordingly decreased.

As a somewhat different method of practicing the invention, I have found that satisfactory results may be obtained by eliminating the benzol in which case the alcohol content is preferably proportionately increased. In this embodiment of the invention, I prefer to employ absolute alcohol rather than the 95 per cent alcohol ordinarily employed.

As stated, ethylene or propylene may be employed or a mixture of the two gases may be used. In practicing the invention, I have found that the gases are substantial chemical equivalents and the term "ethylene" employed in the claims is employed to cover the use of either of the two gases or a mixture of them.

While I have described in detail the preferred practice of my process, it is to be understood that the details of procedure, and proportions of ingredients may be widely varied, and that known chemical equivalents may be employed in place of the materials mentioned, without departing from the spirit of the invention or the scope of the subjoined claims.

I claim:

1. A mixed fuel for internal combustion engines comprising a homogeneous mixture of the gasoline-like fraction of shale oil, alcohol and ethylene.

2. A mixed fuel for internal combustion engines comprising a homogeneous mixture of the gasoline-like fraction of shale oil, alcohol, ethylene and benzol.

3. A mixed fuel for internal combustion engines comprising a homogeneous mixture of the gasoline-like fraction of shale oil, alcohol containing a relatively small amount of ethylene and commercial benzol containing a relatively small amount of toluol.

4. A mixed fuel for internal combustion engines comprising a homogeneous mixture of the gasoline-like fraction of shale oil having nitrogen bases therein, alcohol and ethylene.

5. A mixed fuel for internal combustion engines comprising a homogeneous mixture

- of the gasoline-like fraction of shale oil having nitrogen bases therein, alcohol and ethylene, the ethylene being present in approximately from 2 to 8 per cent of the fuel.
- 5 6. A mixed fuel for internal combustion engines comprising a homogeneous mixture of the gasoline-like fraction of shale oil having nitrogen bases therein, alcohol, ethylene and benzol.
- 10 7. A mixed fuel for internal combustion engines comprising a homogeneous mixture of the gasoline-like fraction of shale oil hav-
- ing nitrogen bases therein, alcohol, ethylene, and commercial benzol containing toluol.
8. A mixed fuel for internal combustion ¹⁵ engines comprising a homogeneous mixture of the gasoline-like fraction of shale oil having nitrogen bases therein, alcohol containing a relatively small amount of ethylene, and benzol containing a relatively small ²⁰ amount of toluol.

In testimony whereof, I affix my signature.

RALPH H. McKEE.
